J. N. BORROUGHS

PROCESS FOR LAUNDERING TOWELS

Filed Oct. 10, 1923

FIG. 2

INVENTOR
JOSEPH N. BORROUGHS

BY
Harry C. Schroeder
ATTORNEY

UNITED STATES PATENT OFFICE.

JOSEPH NEWTON BORROUGHS, OF OAKLAND, CALIFORNIA.

PROCESS FOR LAUNDERING TOWELS.

Application filed October 10, 1923, Serial No. 667,677, and in France November 15, 1923.

My invention is an improved process for laundering roller cabinet towels.

Towels of this character, which are usually about seventy-five feet in length, are very difficult to handle. It is essential that they shall be handled rapidly and with a minimum amount of labor. The washing and wringing operations present the greatest difficulty because of the rotation of the machines which tends to tangle the towels, thus presenting great difficulty to their rapid removal therefrom. To overcome this difficulty I fold and secure the towel in the folded position prior to its insertion into the washer and wringer.

The object of my invention is to provide a process of laundering towels which is rapid, and is carried out with a minimum amount of labor.

Further objects and advantages will be more specifically described and pointed out in the following detailed description.

In the annexed drawing in which I have illustrated the various mechanisms by means of which my process is carried out:

Figure 1 is a transverse sectional view of the towel folder.

Figure 2 is a side view of the towel after it has been secured at the ends.

Figure 3 is a side view of the washer.

Figure 4 is a side view of the wringer.

Figure 5 is a side view of the towel unfastened and ready for ironing.

Figure 6 is an end view of the ironer and roller.

Figure 7 is a side view of the towel rolled and ready for use in a cabinet.

Referring more particularly to the drawing, the soiled towel is caused to enter a folding machine 1, which consists of a roller 2 over which the towel is adapted to travel and a hollow pendulous arm 3, which is swung by a pitman 4 extending from the crank 5, said crank being rotated by any suitable source of power.

The towel is threaded through the arm 3, and the swinging of the arm forms the towel into the bundle 6. The bundle 6 is now secured at the ends by any suitable fastening means, such as the pins 7, which prevent it from unfolding during the following operation. The towel is about seventy-five feet in length and is folded into a bundle about thirty inches long, which is easily handled.

A number of bundles are now easily accommodated in a washer of suitable type and the bundles are washed without being unfolded and are manipulated as small units, without any danger of becoming tangled. They may be removed as units from the washer to the wringer and pass thru the latter. This method of folding the towels facilitates the washing and wringing operations and saves the material of the towels. For ironing a towel, the pins may be removed, which allows the towel to unfold.

Having described my invention, I claim:

1. The method of preparing a relatively narrow towel of unwieldy length for laundering operations, which consists in folding the towel back and forth along transverse lines into equal lengths with alternate folds arranged in aligned relation so as to form a rectangular bundle and in holding the towel in bundle form by interconnecting adjacent folds.

2. The method of preparing a relatively narrow towel of unwieldy length for laundering operations, which consists in folding the towel into a bundle of uniform, short lengths and in interconnecting the lengths for holding the towel in the bundle formation during the laundering operation.

In testimony whereof I affix my signature.

JOSEPH NEWTON BORROUGHS.

CERTIFICATE OF CORRECTION.

Patent No. 1,653,542.

Granted December 20, 1927, to

JOSEPH NEWTON BORROUGHS.

It is hereby certified that error appears in the above numbered patent requiring correction as follows: In the printed specification, strike out the description of Figures 3, 4, 5, 6 and 7; and that the said Letters Patent should be read with this correction therein that the same may conform to the record of the case in the Patent Office.

Signed and sealed this 8th day of May, A. D. 1928.

(Seal)

**M. J. Moore,
Acting Commissioner of Patents.**
